UNITED STATES PATENT OFFICE.

EUGENE BERCIOUX, OF NEW YORK, N. Y.

MOUTHPIECE FOR MUSICAL WIND INSTRUMENTS.

Application filed April 15, 1927. Serial No. 184,087.

This invention relates to improvements in mouthpieces for musical wind instruments, and has particular reference to mouthpieces for clarinets and the like.

5 An important object of the invention, in its broader aspects, is to provide a mouthpiece which will give clearer musical tones and greater volume of sound and better tone quality with less effort on the part of the 10 musician.

Another object is to provide such a mouthpiece wherein a column of air is permitted to expand rather suddenly as it passes through a restricted portion of the chamber, 15 and wherein the air passageway and the chamber are free from impediments to the blown column of air.

More specifically the invention contemplates a mouthpiece in the form of a shell 20 which is provided with an inlet chamber of gradually varying cross-sectional configuration and which, at its inner end, communicates with a discharge passageway into which the column of air is adapted to expand. The 25 inlet end of the chamber, in the preferred form of the invention, is substantially trapezoidal in outline while the major portion of its discharge end is substantially circular in cross-section, and the change from one outline to the other being gradual through the 30 length of the chamber. The improved mouthpiece is further characterized by a secondary chamber portion mutually intersecting the adjacent walls of the main portion of the 35 chamber and the discharge passageway. The discharge passageway is substantially cylindrical and of greater cross-sectional area than the meeting end of the chamber, and may preferably join said chamber in a shoulder 40 rather than merging therewith.

These and other objects, features and advantages will be readily apparent from the following description in connection with the accompanying drawings, wherein one form 45 of the invention has been shown by way of illustration, and wherein,

Figure 1 is a bottom plan view of a mouthpiece embodying the invention;

Fig. 2 is a vertical longitudinal sectional view on the line 2—2 of Fig. 1, and shown for convenience in inverted position;

Figure 3 is a vertical transverse sectional view on the line 3—3 of Fig. 2; and

Fig. 4 is a vertical transverse sectional view 55 on the line 4—4 of Fig. 2.

The improved mouthpiece contemplated

by the present invention may be of any usual or preferred form in its general exterior construction, and may be integrally formed of hard rubber or other desirable material, dependent to some extent upon the particular instrument to which it is to be applied. The mouthpiece shown by way of illustration in the drawings comprises a shell 10 which may be substantially cylindrical throughout the 60 major portion of its length, and provided adjacent its discharge end with a neck portion 11 of reduced diameter, fitted with a suitable gasket 12 of cork or other desirable packing material, whereby the mouthpiece may be 65 inserted in the throat of an instrument and leakage of air positively prevented. Extending inwardly from the discharge end of the mouthpiece is a substantially central cylindrical bore 13, which has its inner end, in 70 communication with a tone chamber 14. The chamber 14 extends inwardly from the tapered inlet end 15 of the shell 10 and is partially covered by a reed 16 of any ordinary or preferred type, said reed being normally 75 held in position on a flattened surface 17 of the shell by means of the usual ligatures, or otherwise, as desired.

As best shown in Fig. 2, the chamber 14 is disposed at an obtuse angle with reference 80 to the axis of the passageway 13, and a characteristic of this chamber is that it varies gradually in cross-sectional configuration, with the result that a column of air blown therethrough produces a finer tone quality 85 than has been possible heretofore. This is a fact which has been substantiated by practice of the invention. The entrance to the chamber 14 is substantially rectangular or trapezoidal, as shown in Fig. 1, having its 90 major base 18 at the tapered end 15 of the mouthpiece and having its minor base 19 and side walls 20 and 21 substantially straight and terminating rearwardly with reference to the inner end of the passageway 13. As 95 the said walls of the chamber 14 are followed inwardly, their contour varies by the formation of merging curves so that the inner end 22 of the chamber is substantially circular in cross-section and approximately 100 concentric with the bore 13. The inner end of the bore 13 is of greater cross-sectional area than the said inner end 22 of the chamber, and the result is that the mouthpiece 105 preferably has a pronounced shoulder 23 at the point of juncture of the chamber 14 with said bore 13, and this variation permits of 110

the rapid expansion of the column of air as it leaves the chamber 14. In addition to this major portion of the tone chamber which has just been described, the improved mouthpiece is characterized by a secondary chamber portion 24 which is defined by a cylindrical wall 25 disposed at an angle and extending from the minor base 19 to the wall of the bore 13 at a substantial distance beyond the shoulder 23. This secondary portion 24 eliminates from the chamber any undesirable resistance to the column of air which would otherwise be present, and the arrangement is such that when viewed as in Fig. 3 the cross-sectional configuration of the interior of the mouthpiece is substantially that of a figure 8, or it might be described as defined by a pair of overlapping circles.

When the improved mouthpiece is in use, the performer blows into it in the usual manner and the resultant column of air passes principally through the major portion of the chamber 14, though some of it, of course, passes through the secondary portion 24 and into the passageway 13. In view of the gradually varying contour of the chamber, the tones produced will be clear and true and the volume of sound will be considerably improved. Furthermore, in view of the rapid expansion of the column of air as it passes the shoulder 23, and its freedom from obstructions in its subsequent passage through the bore 13, the desired tones can be obtained by the performer with less effort on his part. The invention has been thoroughly tested and found to be a very substantial advance in the art because of the above-mentioned improved qualities and characteristics, and while the improved mouthpiece is particularly well adapted for use in clarinets, it may also be used in saxophones, or the like, if desired. By varying the relative proportions of the cylindrical wall 25 and the inner end 22 of the chamber, the invention can be modified for use in instruments of different keys. For example, by increasing the opening in the throat of the chamber the tone volume may be increased, whereas reducing the size of said opening slightly reduces the volume but gives a finer quality. In the prior art mouthpieces of this general character the tone chamber has been substantially square or rectangular, and generally passing into a cylindrical bore without proper freedom for the expansion of the column of air. And in some forms the chamber has been round, giving too much freedom for the air, with a resultant whistling effect. With the present improved mouthpiece, however, there is the necessary freedom from obstructions and ability for quick expansion which provides the improved musical results.

An important feature of the invention resides in the curved arch portion of the mouthpiece, which may be produced by the trans-

versely curved secondary chamber portion 24, such curved arch portion being located beyond the inner end of the entrance to the inclined chamber 14, and such arch portion reinforcing the mouthpiece at the flattened surface to which the reed is applied. Warping in mouthpieces always occurs at substantially the same place, which is caused by the pressure of the reed which is held tight against the mouthpiece by the ligature, and by reason of such arch portion this objection is overcome, particularly in mouthpieces which are made integrally of hard rubber.

Obviously, the invention is susceptible of numerous modifications in the details of construction and arrangements of parts, and the right is herein reserved to make such changes as fall within the scope of the patented claims without departing from the spirit of the invention.

Having thus described my invention, what I claim is:

1. A mouthpiece for clarinets and the like, comprising a shell having an inclined chamber at its entrance end and a relatively straight passageway leading from said chamber to the exit end of the mouthpiece, said chamber having its wall curved transversely and of substantially circular form at its inner end, and said passageway being of larger cross-sectional area than said chamber and the walls thereof having a shoulder formed by the intersection of the chamber with the passageway.

2. A mouthpiece for clarinets and the like, comprising a shell having a substantially central passageway extending inwardly from its discharge end, and having an inclined chamber extending from the inlet end of the mouthpiece and in communication with said central passageway, the cross-sectional configuration of said chamber gradually varying inwardly from substantially trapezoidal to substantially circular at the inner end of the chamber, and the inner end of said chamber being of less area than the meeting end of said central passageway.

3. A mouthpiece for clarinets and the like, comprising a shell having a substantially central passageway extending inwardly from its discharge end, and having an inclined chamber extending from the inlet end of the mouthpiece into communication with said central passageway, the entrance end of said chamber being substantially trapezoidal in outline, and the discharge end of said chamber being defined by overlapped circles in cross-section.

4. A mouthpiece for clarinets and the like, comprising a shell having a substantially central passageway extending inwardly from its discharge end, and having an inclined chamber extending from the inlet end of the mouthpiece into communication with said central passageway, the entrance end of said

- chamber being substantially trapezoidal in outline, and the discharge end of said chamber being defined by overlapped circles in cross-section, the intersection of the walls of 5 said chamber with that of the passageway defining an abrupt shoulder which permits a sudden expansion of a column of air leaving the chamber.
5. A mouthpiece for clarinets and the like, 10 comprising a shell having a substantially central cylindrical passageway extending inwardly from its discharge end, and being further provided with a chamber extending inwardly from the inlet end of the mouthpiece and intersecting said passageway at an obtuse angle, said chamber having a main portion which varies gradually from substantially straight to curved walls in cross-section, and said chamber having a secondary 15 20 portion with a cylindrically curved wall which intersects both said main portion of the chamber and said central passageway.
6. A mouthpiece for wind instruments of the class described comprising a shell having a substantially central cylindrical passageway extending inwardly from its discharge end, and being further provided with a chamber extending inwardly from the inlet end of the mouthpiece to communicate with said passageway, said chamber having a portion 30 which by itself extends into the inner end of said passageway, and having another portion which intersects the side wall of the cylindrical passageway beyond its inner end.
7. A mouthpiece for clarinets and the like, 35 comprising a solid shell having an inclined chamber at its entrance end and a longitudinal passage way leading from the chamber to the opposite end of the mouthpiece, and said chamber having a curved arch portion beyond the inner end of its entrance, which arch reinforces the mouthpiece at the flattened surface to which the reed is applied.

EUGENE BERCIOUX.
